UNITED STATES PATENT OFFICE.

ADDISON C. FLETCHER, OF NEW YORK, N. Y.

IMPROVEMENT IN GRATE-BARS.

Specification forming part of Letters Patent No. 152,736, dated July 7, 1874; application filed December 27, 1873.

To all whom it may concern :

Be it known that I, ADDISON C. FLETCHER, of New York, in the county of New York and State of New York, have invented certain new and useful Improvements in Grate-Bars, of which the following is a specification :

This invention relates to grate-bars, which are provided with detachable fuel bearings or points ; and it consists in securing the fuel-bearings to the grate-bars proper by means of a fastening device which is entirely separate or independent from the grate-bar and point, so as to enable the latter to be firmly retained in position, while not preventing the ready attachment or detachment of the point, to replace it with a new one when burned or worn out, the fastening medium being either in the shape of a screw-rivet or screw-bolt, or other device made separate or distinct from the grate-bar or point.

In the accompanying drawings, Figures 1 and 2 represent views from opposite sides of a grate-bar constructed according to my invention. Fig. 3 is a plan or top view of the same. Fig. 4 is a transverse section through one of the detachable fuel bearings or points, showing the use of a screw for securing the latter. Fig. 5 is a corresponding view, representing a rivet-fastening device.

The letter A designates the body of a grate-bar, which may be formed of a single flat plate, preferably of wrought-iron, or it may be constructed of two or more plates riveted together, to give the requisite thickness. The fuel bearings or points B, which are arranged at the upper edge of the bar, are located at regular intervals apart, and may be cast, or otherwise formed, with a pendent flange or extension-plate, D, at one side, and with a short ear or lip, E, at the opposite side. A fuel-bearing point so constructed embraces the top edge of the body of the grate-bar, and is secured in position by means of a fastening device, which is made entirely separate or independent from either the bar or point, so as to enable the fuel-bearings to be readily applied in position in respect to the bar, and to be quickly detached therefrom when worn and burned out, in order to be replaced by a new point.

In order to carry out my invention I employ either a set-screw, solid rivet, screw-bolt, tubular rivet, or other suitable independent fast-

ening device, F, which passes through the grate-bar and into or through the pendent flange D of the fuel-bearing point.

When a screw is employed I preferably form the female screw-thread in the flange of the fuel-bearing, the threaded end of the screw entering the screw-thread in the flange, and the head of the screw bearing either against the opposite face of the grate-bar or entering a countersunk recess in the latter. A rivet or screw-bolt, when employed, as shown in Fig. 4, to secure the fuel-bearing point, is applied in a similar manner as the screw, the threaded aperture in the flange D being then dispensed with. In certain instances I propose to employ a tubular rivet, which is inserted through the grate-bar body and flange of the fuel-bearing point, and then clinched or riveted.

The method of fastening detachable fuel-bearings to grate-bars, as above-described, is greatly superior in many respects to the plan heretofore practiced, in which the fastening device forms a part of the fuel-bearing and grate bar, for it will be perceived that a simple rivet or screw can be readily applied, and serves also to secure a more permanent fastening, as it will prevent the fuel-point from moving in any direction whatsoever, forming in fact a fastening which will hold the point in a rigid position, without liability of displacement. The fuel bearings or points may be made of cast-iron, and the end ones, as also the central ones, be provided with side projections H, to retain the bars at their proper distances apart, and also to prevent their being displaced by the action of the heat.

Having thus described my invention, what I claim as new, and desire to secure by Letters Patent, is—

The combination of a grate-bar with detachable fuel bearings or points, and independent fastening devices F, for securing the fuel-bearings to the grate-bar to permit of their ready attachment and removal, substantially as and for the purpose set forth.

In testimony that I claim the foregoing, I have hereunto set my hand this 23d day of December, 1873.

ADDISON C. FLETCHER.
